UNITED STATES PATENT OFFICE.

WILLIAM L. CHRYSLER AND JOSEPH W. KAYS, OF EUGENE, OREGON.

PITMAN CONNECTION.

No. 921,363.

Specification of Letters Patent.

Patented May 11, 1909.

Application filed July 9, 1908. Serial No. 442,756.

To all whom it may concern:

Be it known that we, WILLIAM L. CHRYSLER and JOSEPH W. KAYS, citizens of the United States, residing at Eugene, in the county of Lane and State of Oregon, have invented certain new and useful Improvements in Pitman Connections, of which the following is a specification.

This invention contemplates certain new and useful improvements in cutting devices of that type usually employed in mowing machines or similar agricultural instruments, and the object of the invention is an improved coupling that is designed to effectually connect the pitman to the cutter bar, and may be readily operated to cause the pitman to quickly and positively release the cutter bar without the necessity of removing bolts or resorting to other tedious means now employed, in order to permit the detachment of the cutter bar from the machine, as may be desired for repairing purposes or to replace the cutter bar by a new one.

With this and other objects in view that will more fully appear as the description proceeds, the invention consists in certain constructions and arrangements of the parts that we shall hereinafter fully describe, and then point out the novel features thereof in the appended claim.

For a full understanding of the invention and the merits thereof, and to acquire a knowledge of the details of construction, reference is to be had to the following description and accompanying drawing, in which:

Figure 1 is a perspective view of our improved pitman connection applied; Fig. 2 is a horizontal section thereof, showing the jaws associated with the head; Fig. 3 is a similar view, showing the movable jaw in inoperative position and also indicating in dotted lines the position assumed by the clamping member to permit the complete detachment of the jaws from the head; and, Fig. 4 is a detail perspective view of the clamping member.

Corresponding and like parts are referred to in the following description and indicated in all the views of the drawing, by the same reference characters.

Referring to the drawing, the numeral 1 designates the cutter bar which is designed to coöperate with the finger bar of an ordinary cutting device, and which may be of any desired construction or design except

that it is formed at one end with a spherical head 2.

3 designates a pitman which is designed to be eccentrically connected at one end to a rotary element (crank disk) and which is arranged at its other end for connection with the cutter bar so as to impart a reciprocating motion thereto, metal plates being carried at two opposite sides of the pitman near the last named end thereof and projecting beyond such end to constitute spaced jaws, one jaw 4 of which is secured rigidly to the pitman, and the other jaw 4^a of which is secured to and supported upon a flat spring 8 that normally exerts its tension to swing the jaw 4^a outwardly away from the rigid jaw 4 and hold the former in an inoperative relation to the latter, and that extends longitudinally beyond the jaw 4^a, and is rigidly secured at such end to the pitman. The jaw 4^a is designed to be swung inwardly against the tension of the flat spring 8 into operative relation to the rigid jaw, and in order to permit such lateral movement, the corresponding end of the pitman is preferably beveled, as shown. The jaws 4 and 4^a are formed in their opposing walls near their extremities with transversely alining sockets 5 that are arranged to be associated with and engage the head 2 to afford a flexible connection between the pitman and the cutter bar.

In order to hold the movable jaw 4^a in operative relation to the other jaw, we provide a transverse bolt 6 passing between the respective jaws and projecting beyond the movable jaw 4^a, and is arranged to support a clamping member contiguous to the outer face thereof. This clamping member consists of an L-shaped bar 7, one arm of which is preferably longer than the other and which is formed with a longitudinally disposed slot 9 by means of which it is mounted upon the projecting end of the bolt, and is retained thereon by a nut 10, the slot extending substantially throughout the length of the shorter arm of the bar and also extending part of the length of the other arm, and terminating short of an inwardly disposed lug 11 that is formed upon the longer arm of the bar at an intermediate point, as shown, and that is arranged in the normal position of the clamping member to bear against the movable jaw 4^a.

12 designates a retaining bar which is

preferably constructed of spring metal and is rigidly secured at one end to the extremity of the longer arm of the bar 7, and which is normally held in spaced relation to the 5 pitman and is arranged to be swung inwardly toward the latter and held under tension in engagement with a catch 13 carried thereby.

Before proceeding with the description of 10 the operation of our improved connection or coupling, it is to be assumed that the parts are in their normal position, as just described, with the movable jaw in inoperative relation to the rigid jaw, and the retaining bar released from the catch and in spaced 15 relation to the pitman. In order to move the jaw 4^a inwardly to clutch the head 2 of the cutter bar and coöperate with the rigid jaw to establish a flexible and operative connection 20 between the cutter bar and the pitman, the retaining bar 12 is swung inwardly toward the pitman and its free end is engaged with the catch 13 and is held under tension in such engagement. During this 25 movement, and in fact in most of the positions of the clamping bar, the bolt 6 passes through the portion of the slot 9 formed in the longer arm of the bar 7 with the nut supported contiguous to the outer face thereof, 30 so that such nut constitutes a fulcrum about which the clamping member moves upon the movement of the retaining bar, thereby moving the lug 11 inwardly against the movable jaw 4^a to swing the latter toward the rigid jaw against the tension of the flat 35 spring 8 and effect the association of the jaws with the head 2.

When it is desired to render the connection 40 between the cutter bar and the pitman inoperative, the catch 13 is disengaged from the retaining bar 12, thus permitting the parts to assume their normal positions and releasing the flat spring 8 to cause the same to swing the movable jaw outwardly away 45 from the rigid jaw 4. In case it should be desirable or necessary to entirely disconnect the parts of the coupling, that is detach the jaws from the head, the retaining bar is 50 swung to assume a position substantially perpendicular to the pitman, so as to move the bolt 6 through the slot 9 into the portion

of the latter formed in the shorter arm of the clamping member, thus moving the lug 11 out of contact with the movable jaw and permitting the same to yield outwardly under 55 tension sufficiently to disassociate the jaws from the head.

From the above description, in connection with the accompanying drawing, it will be apparent that we have provided a simple, 60 durable and efficient construction of coupling device by means of which the jaws may be held in engagement with the head of the cutter bar against the tension of the flat spring, which may be readily operated to relieve the flat spring of tension and permit the same to positively disassociate the jaws from the head, and which consists of comparatively few parts that may be easily and cheaply manufactured and readily assembled. 70

Having thus described the invention, what we claim is:

In a pitman connection, the combination of jaws formed of stiff material and one of which is rigidly secured to the pitman, a flat 75 spring also secured to the pitman and movably supporting the other jaw and normally exerting a tension thereupon to hold the same in inoperative relation to the rigid jaw, a head adapted for engagement by such jaws, 80 a bolt extending transversely of the jaws and projecting beyond the movable jaw, an L-shaped clamping member formed with a longitudinal slot that extends through both arms 85 thereof and in which works the projecting end of the bolt, one arm of said member being formed beyond the corresponding terminal of the slot with an inwardly disposed lug arranged to impinge against the movable 90 jaw, a yielding retaining bar secured to such lug-carrying arm and disposed in substantially longitudinal alinement therewith, and means for detachably engaging the retaining bar to hold the same under tension and force the lug against the movable jaw. 95

In testimony whereof we affix our signatures in presence of two witnesses.

WILLIAM L. CHRYSLER. [L. S.]
JOSEPH W. KAYS. [L. S.]
